UNITED STATES PATENT OFFICE.

ROBERT T. JOHNSTON, OF TAUNTON, MASSACHUSETTS, ASSIGNOR, BY MESNE ASSIGNMENTS, TO THE AUTOPLATE COMPANY OF AMERICA, OF JERSEY CITY, NEW JERSEY, A CORPORATION OF NEW JERSEY.

STEREOTYPE-MATRIX-MAKING PRESS.

1,103,210.

Specification of Letters Patent. Patented July 14, 1914.

Application filed April 10, 1905, Serial No. 254,658. Renewed November 28, 1913. Serial No. 803,603.

To all whom it may concern—

Be it known that I, ROBERT T. JOHNSTON, a citizen of the United States, residing at Taunton, in the county of Bristol and State of Massachusetts, have invented a new and useful Stereotype-Matrix-Making Press, of which the following is a specification.

The object of this invention is to provide a new and improved stereotype matrix-making press. The press now usually employed for this purpose consists of a steam-heated table coöperating with which is a hand-press. I have discovered that this arrangement can be much improved if a steam cylinder and piston are used to actuate the platen or movable part of the press, because it is necessary to have steam in the table to dry the matrix, and by using steam to actuate the platen, the flowing will be held to the type with a pressure which will cause the press to follow the matrix as it shrinks and dries, without attention on the part of the operator. With the old hand-press, the operator usually has to set the press up several times during the operation, which is apt to distort the matrix. By using a yielding pressure like that obtained from steam or compressed air, the platen will automatically follow up the matrix.

Referring to the drawings and in detail, Figure 1 is a side elevation of an apparatus constructed to embody my invention. Fig. 2 is an end view thereof. Fig. 3 is a sectional elevation through the operating means for the platen. Fig. 4 is a sectional perspective view illustrating the way the matrix is applied to the type, and Figs. 5 to 11 inclusive are elevations of modifications hereinafter referred to.

Referring to the drawing and in detail, B designates an upright steam boiler which has the usual attachments. Resting on top of the boiler is a hollow table T which is also supported at its other end by legs L. The table is connected by pipes 10 and 11 to the boiler so that the surface of the table will be kept at a high temperature. The table at its end may be provided with an adjustable safety valve and steam gage. Secured to the sides of the table are brackets 12—12. Connected to the top of these brackets is an arch 13 in which is formed a cylinder 14.

P designates the platen which is guided

between the brackets 12—12 by suitable pins. A piston rod 15 is connected to the top of the platen, and to a piston 16 working in the cylinder 14, as shown in Fig. 3. Secured to the top of the arch 13 is a projecting cylinder 17. The piston rod 15 extends up into this cylinder 17 and has a projection 18 at its upper end.

A spring 19 is arranged under this projection to bear on the top of the cylinder. The cylinder is connected to the boiler by a pipe 20, which pipe has a valve 21. An outlet pipe 22 having a valve 23 is also connected to the cylinder. A pressure gage 220 is provided in the outlet pipe 22 to connect with the cylinder so that the pressure on the piston can be determined.

In operation, when the form of type is received, it is laid on the end of the table extending to the right as shown in Fig. 1. The matrix which now comprises a flong 75 of soft and wet paper is placed on the form of type and a blanket is placed over the matrix, as shown in Fig. 4. The parts are then slid under the platen. The valve 21 is then opened. This will admit steam to 80 the cylinder, and will force the platen down on top of the blanket to press the matrix firmly into the form of type while the matrix dries. By using this mechanism great pressure is obtained, which pressure may be 85 varied at will, and by which the platen can be very quickly set or put into operation without manual labor. Moreover, it will be noticed that by leaving the pressure on in the cylinder as the matrix is drying, the 90 platen will automatically follow up the matrix as it shrinks, without attention on the part of the operator, whereby a particularly accurate and good matrix will be obtained. After the matrix has dried and set, 95 the inlet valve 21 is closed and the outlet valve 23 is opened, when the spring 19 will quickly raise the platen so that the parts can be pulled out from under the press and the completed matrix taken out.

100 The steam cylinder, piston and spring may be arranged in various ways to operate the platen. In Fig. 5 the cylinder and piston are arranged at the side of the press to operate on a pivoted lever 24 which bears on 105 the top of the platen. The rod 25 extends up from the platen through the arch, and the spring 19 is arranged thereon. In Fig.

6 another modification is shown, in which the cylinder and piston are arranged in a framing 26 above the arch. In Fig. 7 the cylinder and piston are arranged horizontally, and toggle arms 27-27 are employed to actuate the platen. In Fig. 8 the platen is operated by a heavy lever 28. The piston and piston-rod are rigidly secured to the table, and the cylinder is arranged to slide 10 on the piston to actuate the lever 28, the spring 19 in this instance being arranged under the lever. In Fig. 9 the piston is secured to the arch and the piston-rod is made hollow so that steam can be admitted 15 or exhausted therethrough. The cylinder 29 in this instance is formed directly with the platen, and springs 30 are arranged at the edges of the platen to lift the same when the pressure is relieved. In Fig. 10 the cylinder 20 is arranged underneath the table and the piston is connected to an arm or frame 31 which connects by rods 32 passing through lugs on the side of the table up to the platen. The springs 19 in this instance 25 are arranged on said rods between the lugs and the platen. In Fig. 11 a double acting piston is shown which is connected by a lever 33 to operate the platen. Two inlet 30 pipes are employed, one at each end of the cylinder, and two outlet pipes are employed, one at each end of the cylinder. These pipes have suitable valves. Pressure is admitted on top of the piston to set the platen, and when the platen is to be raised the pressure 35 at the top is shut off, and the top of the cylinder is connected so that the steam therein can escape, and pressure is admitted under the piston to raise the same. In some instances compressed air may be advantageously employed to get the yielding 40 action before described.

Many other modifications may be made by a skilled mechanic without departing from the scope of my invention as expressed 45 in the claims.

Having thus fully described my invention what I claim and desire to secure by Letters Patent is:—

1. The combination of a boiler, a matrix drying table mounted thereon, a platen having an area so that the same can be applied over the entire surface of the flong, and a steam cylinder and piston connected to operate the platen so that the flong will be held to the type with steam pressure, where- 50 by the platen will follow the flong as it shrinks and dries. 55

2. The combination of a boiler, a matrix-drying table mounted thereon, a platen co-operating therewith to form a press, a 60 steam cylinder and piston connected to operate the platen, and a spring for raising the platen.

3. The combination of a boiler, a matrix-drying table mounted thereon, a platen co- 65 operating therewith to form a press, an arch connected to said table, a cylinder formed in said arch, a piston working in said cylinder, a connection from said boiler to said cylinder, a small projecting cylinder ar- 70 ranged on top of the steam cylinder, a piston-rod extending between the platen and piston and also up into the small cylinder, a projection on said piston rod, and a spring engaging said projection and acting to raise 75 the platen.

4. The combination of a boiler, a matrix-drying table mounted thereon, connections for admitting steam from the boiler into the matrix drying table, a platen coöperating 80 with said table to form a press, and a steam cylinder and piston connected to said boiler for operating the platen.

In testimony whereof I have hereunto set my hand, in the presence of two subscr- 85 ing witnesses.

ROBERT T. JOHNSTON.
